UNITED STATES PATENT OFFICE.

JOSEPH MERSMAN, OF DELPHOS, OHIO.

HAT-STAND.

SPECIFICATION forming part of Letters Patent No. 333,772, dated January 5, 1886.

Application filed April 21, 1885. Serial No. 162,928. (Model.)

To all whom it may concern:

Be it known that I, JOSEPH MERSMAN, of Delphos, in the county of Van Wert and State of Ohio, have invented a new and Improved 5 Hat-Stand, of which the following is a full, clear, and exact description.

The object of my invention is to provide a new and improved hat-stand which is simple in construction, strong, and durable.

10 The invention consists in a hat-stand made of wires twisted to form a standard having an arm and a ring at its upper end and legs provided with spring-loops at the lower end.

Reference is to be had to the accompanying 15 drawing, forming a part of this specification, in which a perspective view of my improved hat-stand is shown.

The post or upright A is formed of three or 20 more wires, B, which are twisted together. One of the wires B is bent rectangularly at the top of the post to form the arm C, on the end of which a circle or ring, D, surrounding the top of the post is formed. This ring serves to support or hold the hat, bonnet, &c. The 25 lower end of each wire B is bent outward from the lower end of the post, and is bent at its middle to form a loop-spring, E, from which the wire extends downward, the end of the wire being bent to form an eye or loop, F.

The loop-springs E assist in preventing the 30 stand from toppling over in case the hat is too heavy, or is not placed upon the ring D properly.

Having thus described my invention, what I claim as new, and desire to secure by Letters 35 Patent, is—

1. A hat-stand formed of wires twisted together to form a post having an arm on its upper end, on the end of which arm a ring is formed which surrounds the top of the post, 40 substantially as herein shown and described.

2. A hat-stand consisting of a post provided at its upper end with a ring and at its lower end with legs having spring-loops, the whole being formed of wire, substantially as herein 45 shown and described.

3. A hat-stand formed of the wires B, twisted together to form the post A, at the upper end of which an arm, C, is formed, which carries a ring, D, surrounding the top of the post, and 50 at the lower end of which post three or more wire legs, each having a spring-loop, E, are formed, substantially as herein shown and described.

JOSEPH MERSMAN.
